UNITED STATES PATENT OFFICE.

BENJAMIN F. TODD, OF MADISONVILLE, KENTUCKY, ASSIGNOR OF ONE-HALF TO LELAND WOODSON, OF SAME PLACE.

SPROUT-PULLER.

SPECIFICATION forming part of Letters Patent No. 367,328, dated July 26, 1887.

Application filed December 3, 1886. Serial No. 220,582. (No model.)

To all whom it may concern:

Be it known that I, BENJAMIN F. TODD, a citizen of the United States, residing at Madisonville, in the county of Hopkins and State of Kentucky, have invented a new and useful Improvement in Sprout-Pullers, of which the following is a specification, reference being had to the accompanying drawing.

This invention relates to an improved machine for pulling sprouts and grubs, which will be hereinafter more fully described, and pointed out in the claim.

The drawing accompanying and forming part of this specification represents a perspective view of the device applied to a sprout.

A is a yoke having a curved projecting arm, D, with a nipper end, d, at a right angle thereto.

B is a curved lever pivoted within the yoke A by a bolt, C. The curved part E of the lever B has at its end a nipper, e, at a right angle thereto, which is much longer than the nipper d, for a purpose to be hereinafter explained. These nipper ends are opposite to each other and form a clamp.

F is a loop fastened securely to the lever B at f and has a socket, G. The lever B has at its upper end a socket, H. Into these sockets G and H can be inserted a handle, I, by which the device is to be operated in the direction of the arrow.

J is a foot-block of any convenient size and form, which has a rolling fulcrum for the whole apparatus.

The loop F is intended for hand of the operator when the device is to be lifted from one place to another. 35

The operation is as follows: Take the device by the loop F and lift the lever B and handle I, which will permit the nippers d and e to open. As e is longer than d, it will strike against the stem of the sprout to be pulled, which causes it to slip between the crooks on D and E. Then drop the foot-block J to the ground; pull down the handle I in the direction of the arrow, and, as represented in broken lines, the sprout will be pulled from the ground with its roots. 40 45

Having described my invention, what I claim is—

The combination of the yoke A, having a projecting curved arm, D, with its transverse nipper d, and the foot-block J, the lever B, having the hand-loop F, the curved part having the transverse nipper e projecting at its front and outer edges some distance beyond the edges of nipper d, to catch against the stems of the sprouts, substantially as described. 50 55

In testimony that I claim the foregoing as my own I hereto affix my signature in presence of two witnesses.

BENJAMIN F. TODD.
